(57) **CLAIM**

The ornamental design for a laptop, as shown and described.

DESCRIPTION

FIG. 1 is a right, front perspective view of a laptop in a closed position.

FIG. 2 is a top view of the laptop of FIG. 1.

FIG. 3 is a front view of the laptop of FIG. 1.

FIG. 4 is a right side view of the laptop of FIG. 1.

FIG. 5 is a left side view of the laptop of FIG. 1.

FIG. 6 is a right, front perspective view of the laptop of FIG. 1 in a first open position with a keyboard in a first keyboard position.

FIG. 7 is a top view of the laptop of FIG. 6.

FIG. 8 is a front view of the laptop of FIG. 6.

FIG. 9 is a right side view of the laptop of FIG. 6.

FIG. 10 is a left side view of the laptop of FIG. 6.

FIG. 11 is a right, front perspective view of the laptop of FIG. 1 in the first open position with the keyboard in a second keyboard position.

FIG. 12 is a top view of the laptop of FIG. 11.

FIG. 13 is a front view of the laptop of FIG. 11.

FIG. 14 is a right side view of the laptop of FIG. 11.

FIG. 15 is a left side view of the laptop of FIG. 11.

FIG. 16 is a right, front perspective view of the laptop of FIG. 1 in a second open position with the keyboard in the first keyboard position.

FIG. 17 is a top view of the laptop of FIG. 16.

FIG. 18 is a front view of the laptop of FIG. 16.

FIG. 19 is a right side view of the laptop of FIG. 16.

FIG. 20 is a left side view of the laptop of FIG. 16.

FIG. 21 is a right, front perspective view of the laptop of FIG. 1 in a third open position with the keyboard in the first keyboard position.

FIG. 22 is a top view of the laptop of FIG. 21.

FIG. 23 is a front view of the laptop of FIG. 21.

FIG. 24 is a right side view of the laptop of FIG. 21.

FIG. 25 is a left side view of the laptop of FIG. 21.

(Continued)

FIG. 26 is a right, front perspective view of the laptop of FIG. 1 in a fourth open position with the keyboard in the first keyboard position.

FIG. 27 is a top view of the laptop of FIG. 26.

FIG. 28 is a front view of the laptop of FIG. 26.

FIG. 29 is a right side view of the laptop of FIG. 26; and, FIG. 30 is a left side view of the laptop of FIG. 26.

The broken lines showing portions of the laptop and surfaces adjacent broken lines form no part of the claimed design.

1 Claim, 28 Drawing Sheets
